UNITED STATES PATENT OFFICE.

WILLIAM L. BROWN, 4TH, OF PHILADELPHIA, PENNSYLVANIA.

TROLLEY FOR KITES.

Application filed May 19, 1926. Serial No. 110,130.

My invention relates to a reciprocating trolley adapted to be operated upon a kite string, or upon a supporting member positioned between fixed supports, and having sufficient inclination to cause the trolley to slide downwardly by the force of gravity, after it has been forced upwardly, by wind pressure against wings mounted upon the trolley.

The object of my invention is to provide a trolley which will travel back and forth between two stops placed at any desired positions upon the supporting string or member; a further object of my invention is to provide mechanism upon the trolley for holding the wings in the operative or inoperative position; a still further object is to provide double acting shifting means adapted for changing the position of the wings when the trolley strikes a stop in either its upward or downward movement.

Referring to the accompanying drawings, Fig. 1 is a plan view of my improved trolley showing the parts in the position for the wings to be operative; Fig. 2 is a side elevation of Fig. 1; Fig. 3 is a plan view of the trolley showing the parts in the position in which the wings are inoperative; Fig. 4 is a longitudinal vertical section on line 4—4, Fig. 3; Fig. 5 is a transverse section on line 5—5, Fig. 1; and Fig. 6 is a perspective view of the trolley mounted upon a kite string.

In the accompanying drawings, in which like reference characters refer to like parts, 35 10 represents the trolley comprising a body 12, having transverse arms 13 and 14, preferably formed of sheet metal with the edges 15 formed at right angles for increasing the rigidity of the body. At the forward and 40 rear ends of the body are supports 16 and 17 preferably formed of wire with its upper end coiled to form eyes 18 and 19 through which the kite string may be passed for supporting the trolley upon a kite string, or 45 other supporting member 20 and upon which the eyes 18 and 19 freely slide.

The wings 22 and 23 are pivotally mounted upon the outer ends of the arms 13 and 14. The wings are preferably formed of wire 24 formed into a ring, which is covered with cloth or paper 25 as shown in Fig. 4. The ends of the wire 24 are secured in sleeves 26 and 27 pivotally mounted in the arms 13 and 14, which latter are provided with downwardly extending portions 28, which in turn have inwardly extending portions 29, form-

ing bearings in which said sleeves are mounted. Said sleeves have collars 30 secured thereon for holding the sleeves in the bearings in which they are free to turn upon 60 vertical axes, thus permitting the wings to be positioned transversely of the body 12, as shown in Fig. 1, so as to be engaged by the wind blowing parallel with the body and the string 20; or said wings may be 65 swung into a position parallel with the body, as shown in Fig. 3, in which position the wings will not offer any material resistance against the wind, thus permitting the trolley to slide down the string 20 by means of 70 gravity.

The sleeves 26 and 27 to which the wings are rigidly secured are provided with arms 31 and 32 respectively, which are rigidly secured to said sleeves. The opposite ends 75 of said arms are pivotally connected by pins 33 and 34 with links 35 and 36, which links in turn are pivotally mounted upon a pivot head 37 secured to a shift bar 38, in the form of a wire rod slidably mounted in bearings 39 and 40 formed by the end portions of the body 12, which portions 39 and 40 are positioned at right angles to the body 12.

The shift bar 38 is provided with end members 42 and 43 located at opposite ends 85 of the body 12. Said end members are in the form of loops formed by coiling the wire of the shift bar into rings which are open at the end of the coil of wire, which permits the kite string to be embraced within the 90 ring instead of threading the string endwise through the rings.

Said end members 42 and 43 of the shift bar are adapted to take against the stops A and B which may be placed at any desired position upon the string 20, as shown in Fig. 6. When the end member 43 of the shift bar 38 strikes the stop B, in the downward movement of the trolley along the string, the stop B will move the shift bar 38 in relation to the body 12, which movement of the shift bar will open the wings into the position shown in Figs. 1, 2, 5 and in full lines Fig. 6. The links 35 and 36 when in this position act as a toggle and hold the wings at right angles with the body 12, as shown in Fig. 1. The pivot head 37 strikes against the front end bearing 39 of the body thus limiting the forward movement of the shift bar 38. In the forward 110 position of the shift bar as shown in Figs. 1 and 2, the pivot head 37 is slightly beyond.

a line extending between the pivot pins 33 and 34, thus forming a lock adapted for holding the wings in the position shown in Fig. 1, against wind pressure in the direction of the arrows Fig. 1, and when the wings are in this position the wind will move the trolley up the string towards the stop A.

When the trolley travels up the string 20 and reaches the stop A, the forward end member 42 of the shift bar 38 will strike against the stop A, which will move the shift bar longitudinally in relation to the body 12 until the pivot head 37 strikes the guard member 45 on the body 12, thus bringing the links and the wings into the position shown in Figs. 3, 4 and in dotted lines Fig. 6. When the wings are thus shifted into a position parallel with the body 12 and the string 20, as shown in Fig. 1, the wind will cease to act against the wings and the weight of the trolley will cause it to slide down the string until it strikes the stop B, which latter will re-set the wings, into the position shown in Fig. 1, and in full lines Fig. 6 so that the wind will again force the trolley up the string.

The shift bar 38 is provided with a pin 48 upon which an article may be carried until the upper stop A shifts the parts into the position shown in Fig. 4, when the pin 48 will be withdrawn from the guard member 45 and the bearing member 40, which will force the article off the pin 48 and cause it to fall from the trolley.

35 The operation is as follows: The stop A may be placed at any point upon the string 20; the trolley is placed upon the string by turning the string into the open spiral rings 42, 18, 19 and 43. The trolley is supported by the rings 18 and 19 upon the string; the wings are set in the open position, as shown in Fig. 1 and full lines in Fig. 6; and the trolley released so that the wind will force it up the string; the stop B is then placed 40 upon the string, and the trolley will travel back and forth upon the string between the stops A and B. The wings will be automatically shifted into the inoperative position by the impact of the trolley against the stop A and the wings will be automatically 45 re-set by the impact of the trolley against the stop B without any further attention from the operator. The kite string may be paid out until the stops A and B are far 50 from the operator and the trolley will continue to travel back and forth between the stops.

Various changes in the construction and arrangement of the parts of my device may 60 be made without departing from my invention.

I claim:

1. A trolley adapted to travel upon an inclined member between stops secured upon the latter, a wing upon the trolley adapted

for moving the latter up said inclined member by wind pressure, and mechanism upon the trolley adapted for shifting the wing into and out of wind engaging position alternately upon impact with said stops.

2. A trolley adapted to travel upon an inclined member having stops secured thereon, wings movably mounted upon the trolley, and mechanism upon the body adapted for moving the wings into operative position by impact with a stop in the path of the trolley when the latter is moving in one direction and adapted for moving the wings into the inoperative position by impact with a stop in the path of the trolley when traveling in the opposite direction.

3. A trolley adapted to reciprocate upon an inclined member having stops positioned upon said member, wings upon said trolley for moving the latter up the inclined member, mechanism upon the trolley for shifting the wings out of wind engaging position upon impact with a stop located at the upper portion of said member, and mechanism upon the trolley for shifting the wings into wind engaging position upon impact with a stop upon the lower portion of said member.

4. A trolley adapted to travel upon an inclined member, a body adapted to be supported upon said member, a wing pivotally mounted upon the body, a shift bar slidably mounted upon the body, said shift bar having end members positioned at opposite ends of the body and in spaced relation to the latter adapted for engagement with stops upon the inclined member for moving the shift bar in either direction relatively to the body, and means operatively associated with the shift bar and the wing for moving the latter into and out of operative position.

5. A trolley adapted to travel upon an inclined member, a body adapted to be supported upon said member, wings pivotally mounted upon said body, a shift bar slidably mounted upon the body, toggle links pivotally connected with the shift bar, arms having one end rigidly secured to said wings and their opposite ends pivotally connected with said links, a stop upon the body adapted for limiting the movement of the shift bar in one direction, said links adapted to lock the wings in wind engaging position when the shift bar is located adjacent to the said stop, and a member upon the shift bar extending beyond the end of the body adapted to take against a stop positioned upon the inclined member adapted for moving the shift bar to release the wings from operative position.

6. A trolley adapted to travel upon an inclined member, a body adapted to be supported upon said member, wings pivotally mounted upon said body, a shift bar slidably mounted upon the body, toggle links

pivotedly connected with the shift bar, arms having one end rigidly secured to said wings and their opposite ends pivotedly connected with said links, and end members upon the shift bar positioned at the forward and rearward ends of the body in spaced relation to the latter adapted for moving the shift bar when actuated by impact against stops secured upon the inclined member.

10 7. A trolley comprising a body, supports upon opposite ends of the body adapted to slide upon an inclined member, arms upon the body, bearings formed upon the outer ends of the arms, a sleeve loosely mounted

in each bearing, a wing carried by each sleeve, an arm secured to each sleeve, links pivoted to said arms, a pivot head to which said links are pivoted, a shift bar to which the pivot head is secured, bearings formed upon the body upon which the shift bar is 15 slidably mounted and end members upon the shift bar positioned in spaced relation with the ends of the body adapted to be engaged by stops positioned upon the inclined member.

20 25 In testimony whereof I affix my signature.

WILLIAM L. BROWN, 4TH.
